UNITED STATES PATENT OFFICE.

CHAUNCEY D. SHUPP, OF NEHAWKA, NEBRASKA, ASSIGNOR OF ONE-THIRD TO
ABRAHAM L. GRIFFITH, OF NEHAWKA, NEBRASKA.

SASH-PULLEY.

1,208,673.

Specification of Letters Patent. Patented Dec. 12, 1916.

Application filed April 22, 1916. Serial No. 92,875.

To all whom it may concern:

Be it known that I, CHAUNCEY D. SHUPP, a citizen of the United States, and a resident of Nehawka, in the county of Cass 5 and State of Nebraska, have invented a new and Improved Sash-Pulley, of which the following is a full, clear, and exact description.

This invention relates to sash pulleys for use with window frames and similar constructions, and has reference more particularly to a sash pulley which comprises a body having spaced sides and a sheave or pulley wheel journaled between the sides, 15 the body having a part adapted to seat upon the top of a window frame and constituting means for the attachment of the device to the window frame, the body also having a part adapted to rest against the side of the 20 window frame, below the top thereof.

An object of the invention is to provide a sash pulley which can be securely fastened to the window frame, without mortising or countersinking, by means of which orifices 25 giving rise to drafts can be eliminated, and which can be used with equal facility with mortised top and flat top window frames.

The invention consists in the construction and combination of parts to be more fully 30 described hereinafter and particularly set forth in the claims.

Reference is to be had to the accompanying drawings forming part of this specification, in which similar characters of reference indicate corresponding parts in all the 35 views, and in which—

Figure 1 is a side elevation of the upper part of a window frame, showing one form of my invention applied thereto; Fig. 2 is a 40 side view of the upper portion of a window frame, showing two of the sash pulleys mounted upon the frame; Fig. 3 is a perspective view of one form of my sash pulley; Fig. 4 is a view similar to Fig. 45 1, showing a different form of the sash pulley applied to the window frame; Fig. 5 is a view similar to Fig. 2, illustrating two of the sash pulleys shown in Fig. 4; and Fig. 6 is a perspective view of the last-mentioned 50 form of my invention.

Before proceeding to a more detailed explanation of my invention it should be understood that the two forms of the device illustrated and described herewith are for use respectively, with mortised top window

frames, and flat top window frames. Of these, the former are generally used in frame buildings and the latter in stone or brick buildings.

Referring more particularly to the drawings, Figs. 1, 2 and 3, the window frame has sides 10 and a top 11, the sides being extended above the top and having the ends of the latter mortised thereto. Within the frame are slidably mounted the window 65 sashes 12, to which the ends of the sash cords 13 are fastened. At the opposite ends, the sash cords have the usual sash weights 14.

I prefer to fashion my sash pulleys from sheet or plate metal. The body of the device is produced by bending the plate or sheet upon itself so that spaced sides 15 are formed which are joined by a preferably rounded top 16. Journaled between the upper parts of the spaced sides 15 is the sheave 70 or pulley wheel 17 mounted upon a suitable trunnion or pintle 18. Near their rear edges, the sides 15 have upwardly extending slots or cutaway parts 19 which are substantially parallel to the rear edges of 75 the sides. These slots form downwardly extending feet 20. I prefer to have the forward or outer edges of the slots inwardly bent to form parallel flanges 21. The outer edges of the sides 15 are inwardly inclined 80 and the sides thus form tapered extensions 22.

The form of the sash pulley above described, when in position, receives the projecting upper end 10^a of the window frame 90 side 10, the feet 20 resting upon the top 11 of the window frame, and the extensions 22 against the side 10, as is clearly shown in Fig. 1. With this construction of window frame no other means are necessary for fastening the sash pulley in position. It may be desirable to have the slots 19 of such size that the device can be driven firmly into position upon the end of the frame side 10. The frictional contact thus obviates the necessity for otherwise securing the sash pulley in place.

It will be understood that it is customary to employ two sash pulleys, as is shown in Figs. 2 and 5. These are preferably mounted side by side, as illustrated.

The window frame shown in Figs. 4 and 5 has sides 23 and a top 24. The sashes 25 are slidably mounted within the frames, and have the ends of the sash cords 26 attached 110

thereto. At the opposite ends, the sash cords are attached to the usual sash weights 27. The second form of my device is likewise preferably fashioned from sheet or plate 5 metal bent upon itself to form two spaced sides 28 connected by a rounded top 29. At the rear, and below the top, the sides are cut away at 30. The outer edges of the sides are like in the first-described device, in- 10 wardly inclined, and form tapered extensions 31 at the lower portions thereof. At the top of the extension 31 the sides have outwardly-bent parts 32 forming oppositely disposed feet. The pulley wheel or sheave 15 33 is journaled between the upper parts of the sides 28, by means of a suitable pintle or trunnion 34. This form of my invention is arranged to seat at the upper corners of the window frame as is shown in Figs. 4 20 and 5, the feet 32 resting upon the top 24, and the extensions 31 against the sides 23. To secure the device in place, screws or nails 35, driven into the window frame through the openings provided for the purpose in the 25 feet 32, are employed.

It will be understood that the sash cords pass over the pulley wheels or sheaves in the usual manner, openings for the sash cords being provided in the top of the window frames.

If so desired, the form of my invention shown in Figs. 1, 2 and 3, may be provided with nail or screw holes 21^a, near the lower ends of the flanges 21. These openings are 30 adapted to receive screws or nails serving to hold the device against lateral displacement, should it be necessary.

Having thus described my invention I claim as new, and desire to secure by Letters 40 Patent:

1. A sash pulley mounting comprising a single strip of sheet metal bent upon itself to form a pair of spaced apart downwardly extending side members, and a sheave jour-

naled between said side members, said side 45 members having feet at the rear adapted to rest upon the top of the window frame, and having downward extensions, the rear edges of which are adapted to lie against the vertical end of the window frame. 50

2. A sash pulley comprising a body fashioned from sheet metal bent upon itself to form spaced sides, and a sheave journaled between said sides, said sides having at the rear, feet adapted to rest upon the top of a 55 window frame, and having at the front spaced downward extensions the front edges of which are adapted to rest against a side of the window frame.

3. A sash pulley comprising a body hav- 60 ing spaced sides, and a sheave journaled be- 65 tween said sides, said sides being cut away at their rear edges to form feet adapted to rest upon the top of a window frame and having at their lower ends spaced exten- 70 sions 65 the rear edges of which are adapted to rest against a side of the window frame, below the top thereof, said feet constituting means for attaching the device in place.

4. A sash pulley comprising a body fash- 75 ioned from sheet metal bent to form spaced sides, and a sheave journaled between said sides, near the top thereof, said sides being cut away at their rear edges to form feet 80 adapted to rest upon the top of a window frame, and having at their lower ends spaced apart tapered extensions the rear edges of which are adapted to rest against a side of the window frame, below the top thereof, said feet constituting means for attaching the device in place upon the window frame.

In testimony whereof I have hereunto signed my name in the presence of two sub- 85 scribing witnesses.

CHAUNCEY D. SHUPP.
